UNITED STATES PATENT OFFICE.

PAUL JOCHUM, OF OTTWEILER, PRUSSIA, GERMANY.

BRICK-KILN.

SPECIFICATION forming part of Letters Patent No. 404,198, dated May 28, 1889.

Application filed January 4, 1889. Serial No. 295,415. (No model.)

To all whom it may concern:

Be it known that I, PAUL JOCHUM, of Ottweiler, in the Kingdom of Prussia and Empire of Germany, have invented certain new and useful Improvements in Kilns, of which the following is a specification.

This invention relates to an improved kiln which can be worked either continuously or intermittently with an almost complete utilization of the fire-gases, the kiln being arranged so that the fire-gases are conducted in an overlapping course over the bricks or other articles to be burned; and the invention consists, first, of a kiln composed of a number of ovens, each oven having a number of fire-places in its longer sides, and fire-walls at the interior of and parallel to the longer side walls of the combustion-chamber, channels connecting the fire-places with the spaces between the main walls and interior walls, draft-openings in the bottom of the combustion-chamber, and of flues connecting said opening with a ring-shaped flue below said bottom which communicates by radial channels with the central smoke-flue.

The invention consists, secondly, of a kiln having a combustion-chamber, a ring-shaped draft-flue below the bottom of the same, and a communicating smoke-flue, which latter connects with an S-shaped transmitting-flue that connects the combustion-chamber of the first oven with branch flues located below the second oven, said branch flues communicating by valves with the S-shaped flue, and by vertical flues with openings in the bottom of the combustion-chamber, so as to transmit the products of combustion and the heated air from the first oven to the second oven.

The invention consists, thirdly, of a kiln, the combustion-chamber of which has a number of fire-places located at opposite sides, said fire-places being provided with pillars at their rear ends and connected by vertical flues at both sides of the pillars with openings in the bottom of the combustion-chamber between the main walls and the interior fire-walls of the same, while intermediate vertical flues establish communication between the bottom of the combustion-chamber and branch flues that are connected by an S-shaped transmitting-flue with the combustion-chamber of the adjoining ovens.

The invention consists, further, of certain details of construction and combination of parts, which will be fully described hereinafter, and finally pointed out in the claims.

In the accompanying drawings, Figure 1 represents a horizontal section of my improved oven on line xx , Fig. 2. Fig. 2 is a vertical longitudinal section on line yy , Fig. 60 1. Fig. 3 is a vertical transverse section on line zz , Fig. 1; and Figs. 4 and 5 are diagrams showing, respectively, the branch flues and S-shaped transmitting-flues and their connection with each other.

Similar letters of reference indicate corresponding parts.

The kiln is preferably formed of two or more ovens, which are arranged longitudinally in line with each other, each oven being made of oblong shape and provided at its longer sides with six fire-places, f' to f^6 —three on each side—each of which is provided with a step-shaped inclined grate and a horizontal grate, to which the fuel is fed through a supply-opening, o , at the top of the fire-places, as shown clearly in Fig. 3. The ash-pit of each fire-place is provided with a hinged iron door, which is partly or entirely closed when the kiln is in operation, so as to regulate the admission of the cold air to the fire-place. At the rear end of each fire-place is arranged an upright pillar, p , of good refractory material, which divides the fire-place and conducts the fire-gases by two upright flues, p' —one at each side of the pillar p —to openings arranged in the bottom of the combustion-chamber A along the longer sides of the same. The fire-gases pass in upward direction between the main walls and interior fire-walls, A' , up to the arched top of the combustion-chamber, and are then drawn in downward direction toward a number of openings, a , located in the bottom of the combustion-chamber, and then conducted by flues a' to a ring-shaped flue, R , below the bottom of the combustion-chamber, and from the same by radial channels a^2 to a central smoke-flue, Z .

The apertures a in the bottom of the combustion-chamber, the flues a' , the ring-flue R , and the radial flues a^2 produce a uniform distribution of the fire-gases in all parts of the combustion-chamber, even in the corners of the same, as the bottom apertures are

so located as to draw the fire-gases evenly into all parts of the combustion-chamber. The ashes which are carried along by the fire-gases are deposited in the ring-shaped flue R, while the fire-gases are conducted downward in the smoke-flue Z to an S-shaped transmitting-flue V and from the end of the same through valves g g' into flues W² and W³ of the next adjoining oven A. Each flue 5 W² and W³ branches out into two separate flues, which pass both vertically below the spaces located between the main side walls and fire-walls, and communicate by vertical flues s, located intermediately between the 10 flues p', leading from the fire-places into the combustion-chamber, with the spaces between the side walls and interior fire-walls, A'. The arrangement and direction of the branch flues W² and W³ are clearly shown in Fig. 4, 15 while the branch flues W² communicating with one half of the vertical flues s of the second oven, while the branch flues W² communicate with the upright flues s at the other half of the 20 combustion-chamber.

25 The S-shaped transmitting-flue V and the branch flues W² and W³ serve to conduct the fire-gases and the air heated in the combustion-chamber of the first oven into the second oven, where they mingle in the spaces 25 between the side walls and fire-walls with the products of combustion supplied from the fire-places of the second oven, so as to produce thereby the more perfect combustion of the fire-gases and the heated air carried along 30 with the same. It is therefore possible, by closing the doors of the ash-pits, to subject the fuel on the grates of the fire-places to partial combustion and generate carbonic-oxide gas from the same, which is burned in 35 the combustion-chamber, and then supplied 40 the so reduced fuel on the grates directly with air by opening the ash-pit doors and entirely burning the fuel, whereby a more complete and economical utilization of the same 45 is obtained.

The valves g g' establish the connection between the transmitting-flue V and the branch flues W² and W³, which latter conduct the fire-gases to all the corners of the combustion-chamber and permit the regulating of the heat in the combustion-chamber as required by the change in the same. The fire-gases and the heated air are again drawn from the second oven and conducted to the 55 third oven and mixed therein with the direct products of combustion from the fire-places, as just described for the second oven, and so on.

The S-shaped transmitting-flues V V' overlap each other at the ends, as shown clearly on the diagram in Fig. 5, the flues V communicating by the valves g g' with the branch flues W² W³ of the adjoining oven, while the adjoining end of the second transmitting-flue V' communicates by a second set of valves g g' with the branch flues W and W' of the first oven, as shown clearly in Figs. 1,

4, and 5. The S-shaped transmitting-flues permit the connection with the branch flues W W' W² W³, &c., in forward or backward 70 direction, so that a continuous working-kiln is obtained even with three ovens, as the fire-gases can be conducted in a straight line from one oven to the other and returned backward in the same manner from one oven to the other. If one of the ovens—for instance, the second oven at the right-hand side in the drawings—is to be cut out for removing the charge in the same, the valve g², which is arranged in the bottom of the S- 75 shaped transmitting-flue V, is raised, while the valves g g', leading to the branch flues W² and W³, are closed, so that the fire-gases are drawn through the auxiliary flue F', located below the flues V V', into the main smoke-flue F³, and thereby either directly to the chimney, or the fire-gases are conducted (for utilizing the heat still contained in the same) through the main smoke-flue F³ to the lateral auxiliary flue F² and to the transmitting-flue V² of the third oven, so that in this 80 manner the products of combustion from the first oven can be conducted around the second oven to the third oven and utilized in the same. By the auxiliary flues, which are 85 connected by valves with the main smoke-flue F³, any one of the ovens can be cut out and the remaining ovens connected, so that no interruption in the continuous working of 90 the same takes place.

The advantages of my improved kiln are, that by the overlapping fire-gases a uniform heat can be kept up in all the ovens, and that the kiln, by the arrangement of a third oven, be used continuously, or, if preferred, operated intermittently, as desired.

The construction of the kiln is comparatively simple and inexpensive and the saving in fuel considerable, owing to the perfect utilization of the fire-gases generated by the fuel in the fire-places in the combustion-chamber of the ovens.

Having thus described my invention, I claim as new and desire to secure by Letters Patent—

1. The combination, in a kiln, of a combustion-chamber, fire-places at both sides of the same, fire-walls located parallel to the side walls at the interior of the combustion-chamber, flues connecting the fire-places with the spaces between the side walls and fire-walls, draft openings and flues in the bottom of the combustion-chamber, a ring-shaped flue below said bottom, a central smoke-flue, and radial channels connecting the ring-shaped flue with the smoke-flue, substantially as set forth.

2. The combination, in a kiln, with the combustion-chamber, a ring-shaped flue below the bottom of the same, draft-flues connecting the bottom of the combustion-chamber with the ring-shaped flue, a central smoke-flue, radial channels connecting the ring-shaped flue with the smoke-flue, an S-shaped

transmitting-flue connecting the combustion-chamber of the first oven with the second oven, branch flues communicating by valves with the **S**-shaped transmitting-flue, and vertical flues connecting the branch flues intermediate of the direct flues with the bottom of the combustion-chamber, substantially as set forth.

3. The combination, in a kiln, of the combustion-chamber having a number of fire-places located at opposite side pillars of the rear ends of the fire-places, flues at both sides of the pillars communicating with the bottom of the combustion-chamber, intermediate vertical flues, and branch flues connecting said intermediate flues with the combustion-chambers of the adjoining ovens, substantially as set forth.

4. The combination, in a kiln, with the combustion-chamber, draft-flues in the bottoms of the same, a ring-shaped flue below the bottom, radial channels, a central smoke-flue, an **S**-shaped transmitting-flue, and valved auxiliary flues leading the fire-gases from the **S**-shaped transmitting-flue of one oven around the adjoining oven to the branch flues of the third oven, substantially as set forth.

In testimony that I claim the foregoing as my invention I have signed my name in presence of two subscribing witnesses.

PAUL JOCHUM.
